UNITED STATES PATENT OFFICE

JESSE E. LANGSDORF, OF WOODMERE, NEW YORK

NECKTIE

Application filed August 10, 1925. Serial No. 49,349.

My invention relates to certain new and useful improvements in neckties, and especially to that class of ties generally known as bat or bow ties. It has for its object the production of a tie having greater durability than those heretofore in use, one which can be more readily and attractively tied; and, in addition, a tie which, within limits, is adjustable with respect to its length, so that the stock required to be carried by the dealer, to supply various sizes of ties, need not be so great as heretofore. Other objects of my invention will appear from the following description.

15 Bat wing ties, as heretofore made, usually consisted of a silk cover, and an interlining of such character as would furnish the necessary body or stiffness to the finished tie. In the manufacture of such ties, it has been customary to take two pieces of silk, cut to the shape of the tie but a trifle wider, place the faces of the silk together, lay the interlining upon the silk, and machine-stitch the three pieces together along the edges except for a 25 space of about one inch near the center of one side of the tie, which small portion was left open. Through this aperture the tie was turned, and this opening being then closed, the tie was pressed into shape, and formed a 30 fairly satisfactory article. It will be apparent, however, that in such ties, the portions of the lining, extending outside of the machine stitching, will be turned over upon turning the tie; and these portions, even if pressed flat after the turning operation, will form a 35 double thickness of material or ridge entirely around the edges of the tie. If the lining material is fairly heavy as compared to the silk used, the ridge is very perceptible 40 and unsightly, and should the lining material be of such a character that it does not readily crease, the turned over edge will not lie flat, but will form a distinct and unsightly rib or ridge along the edges of the tie, seriously impairing its appearance.

45 The linings heretofore generally used in such ties have been made of canton flannel, muslin, canvas or other cotton material; and, while such materials are creasable and may 50 stay flat after pressing, they are for that

reason readily subject to being wrinkled; and ties having such linings soon get out of shape and become unsightly.

I have found that four-in-hand ties having a lining made from a fabric not subject to permanent distortion, such, for instance, as a woven woolen fabric, when cut and incorporated in a special way, possess very substantial advantages. An important object, therefore, of the present invention is the construction of a tie of the bat or bow type, employing a lining which is not easily distortable. In addition, my tie possesses other substantial advantages, in that it can be readily and attractively tied, and easily untied; and, 60 within limits, is adjustable with respect to its length.

In the manufacture of neckties the silk material is frequently cut upon the bias, chiefly for artistic reasons. Strips of silk, however, when cut on the bias, are stretchable, and, to a limited extent, elastic. That is, a strip of silk, say thirty inches long, may be pulled and elongated an inch or more without physically displacing the adjacent threads of the 75 material; and when the pull is released, the material will spring back to substantially its original condition and dimension. To this extent it is elastic. If, however, such a strip of silk is subjected to an excessive strain or 80 pull—one sufficient to physically displace some of the adjacent threads—the strip will be permanently distorted, will have permanent longitudinal creases, and, when the strain is removed, will only spring back partially. It will never return to its original dimension, unless restored by some extraneous 85 means.

This limit of elasticity or yieldability without distortion varies, of course, with silks of 90 different weights and characters of weave, but the pulling strain to which ties are subjected in adjusting them between the folds of the collar is usually beyond the elastic limit of all silks generally used in necktie 95 manufacture, and is far beyond the elastic limit of light weight silks, such as foulards, crepes, or the like.

In the previous manufacture of neckties, efforts have been made to prevent or mini- 100

imize this tendency to distortion, and the method generally adopted was the provision of a longitudinally rigid lining, to which the silk was firmly secured. On the other hand, I have pointed out in a previous Patent, No. 5 1,447,090, granted February 27, 1923, a different method of construction whereby stretchability within the elastic limits of the fabric was permissible, employing in my construction a lining of limited elasticity, but 10 one sufficiently strong to withstand, without distortion, all pulling strains likely to be met with in service. In the form of tie disclosed in said invention, I employed, as a preferable lining material, a piece of bias cut woven fabric of a material such as wool, which would 15 stretch to a certain extent without having its elastic limit exceeded by the pulling strain, and such ties in the form of four-in-hands have gone into extensive use. Such a lining, 20 when incorporated in the novel manner devised by me, permits the silk to stretch within its elastic limit, and not only permits, but assists, if necessary, in restoring the silk to its original condition, when the pulling strain 25 is removed. In addition, such a lining possessing fiber resiliency as well, was difficult to crease, and therefore resisted the wrinkling tendencies, and produced a tie having 30 great durability and wearing qualities.

In the manufacture of bat wing or turned ties, however, it will be appreciated that the use of such a lining was practically impossible, if the previous manufacturing methods were employed. The lining material was 35 of such a character that it interfered seriously with the turning operation, the edges of the material catching in the threads of the silk during the turning operation and, in addition, it was difficult, if not impossible, to 40 press down the lining along the machine stitching so that it would lie flat after the tie was turned.

By my present invention I have overcome 45 these difficulties, and am able to produce a tie of the bow type, having a lining not readily subject to distortion and, in addition, one possessing great durability as well as other advantages.

One form of my invention is clearly illustrated in the accompanying drawings, 50 wherein:

Fig. 1 is a plan view of a finished tie made in accordance with my invention;

Fig. 2 is a longitudinal section taken 55 through the center of Fig. 1;

Fig. 3 is a plan view of a necktie sewed up, ready for turning (the end of one lining member being broken away);

Fig. 4 is a similar but enlarged fragmentary view showing the method of fastening the lining to one end of the tie;

Fig. 5 is a longitudinal sectional view, taken approximately through the center of 60 Fig. 4; and

Fig. 6 is a view of a tie end, showing the turning operation already begun.

Similar numerals indicate like parts throughout all the drawings.

In the manufacture of my tie, I prefer to proceed as follows: A pair of similar blanks 70 of silk 1, and 2, are cut to shape, but slightly larger than the intended tie. The silk is preferably cut on the bias for artistic reasons and for purposes to be hereinafter pointed out. These blanks are then superposed and are then united by stitching 3, 3, extending along the longitudinal edges thereof except for a small space 4, usually about an inch, which is left unstitched to form an aperture 75 through which the tie may be turned. In addition to the longitudinal stitching 3, 3, the ends are stitched across at 5, 5, which latter stitching forms the ends of the tie 80 when finished and turned. The stitching may be of any desired character, although I prefer to use a machine stitch which will have a certain degree of longitudinal stretchability. This is not absolutely essential, however, as it is apparent that as this stretching does not 85 follow a straight line, but curves as it extends from the neckband to the wider portions of the tie ends, a certain amount of stretchability will be possessed by a tie wherein the stitching is a substantially rigid machine 90 95 stitch.

The blanks thus united are now ready for the insertion or attachment of the lining, and in the preferred form of my invention I employ two lining members 6 and 7, comprising strips of material having limited longitudinal elasticity or resiliency, such, for instance, as a bias cut woven wool fabric, of such weight and character that it will not 100 be permanently distorted by any reasonable pull to which it may be subjected in adjusting the tie around the neck of the user.

The lining members are preferably cut to shape so as to substantially fill the pockets formed by the stitching 3 and 5 when the 110 silk members are turned, and the smaller ends 8 and 9 of the lining are of such length that when adjusted in the turned tie, as shown in Fig. 2, they will slightly overlap. When the silk members have been united by the stitching 3 and 5, as above described, the lining members are inserted by slipping the larger ends thereof into the shallow outer pockets formed in the ends of the silk by the stitching 3 and 5. The larger ends of the 115 lining members may be pushed to the bottom of these shallow pockets against the stitching 5, in which case the stitching serves as an aligning means for insuring the proper placement of the members.

In Fig. 4 the end of the lining member is shown as inserted to a slightly lesser degree, but it is so illustrated to more clearly indicate the parts therein shown. When the 120 wider ends of the lining members are in 125 130

serted and properly disposed between the folds of silk, a further row of stitching 10 is provided, thereby securely uniting the ends of the silk and the ends of the lining member together. The tie is then ready for

5 the turning operation. This may be accomplished by any suitable method, although I prefer to use that generally employed in the manufacture of turned ties, namely, turning upon a blunt headed stick.

10 Fig. 6 shows the disposition of the parts after the turning operation has been started, while Fig. 2 shows the relation of the parts after the tie has been completely turned. In the latter figure it will be noted that the lining members 6 and 7 lie perfectly flat throughout the entire length of the finished tie, and that these members are not turned and have no crease even at the outer ends 15 where it is stitched to the silk. The inner ends of the lining members overlap, as shown; and after they have been disposed in the overlapped position shown in Fig. 2, the aperture 4 is then sewed up. I prefer 20 to secure the parts together by stitching 11, 11, passing through the silk as well. A label 12 may also be stitched upon the back of the tie, as shown, where desired. The tie may then be pressed, and is ready for use.

25 It will be noted that in the construction above described, a lining of limited elasticity is provided, which is secured to the body only at the ends and in the neckband; and, as it substantially fills the inside of the tie and is 30 not creasable, it tends to resist any tendency to wrinkle or crease, which the tying of the tie tends to produce. At the same time, the lining is substantially flat and without creases throughout the entire length and 35 breadth of the tie, and so produces no unsightly ribs or ridges. In addition, the lining possesses limited longitudinal elasticity or resiliency, and will stretch during the tying operation or in response to a moderate pull, 40 say, an inch to an inch and a half or more in a thirty inch tie. This stretch, however, is substantially less than the elastic limit of practically all silks used in the manufacture 45 of such ties, so that the limited yielding of 50 the lining will not be sufficient to permit the silk to be permanently distorted, and if proper stitching is employed in the construction of the tie, the elasticity or yield of the lining will not be sufficient to put any undue 55 strain upon the threads used in the stitching.

This ability to yield or stretch and return to its original shape, is an exceedingly valuable characteristic in bow or bat ties. For instance, a satisfactory length of a bat tie for 60 a $14\frac{1}{4}$ inch collar is about twenty-nine inches, while a satisfactory length for a $15\frac{1}{4}$ inch collar is about thirty inches. When it is appreciated that collars in common use range from $13\frac{1}{2}$ to 17 inches or more, it will be 65 seen that to supply any reasonable demand,

a dealer is required to carry six or eight sizes of bat ties constantly in stock, and where he wishes his line complete, he is required to carry all of these sizes in every style or pattern.

70 Ties made according to my present invention, however, have a stretchability of from one to two inches or even more; so that it will readily be seen that by their use the stock of ties required to supply the reasonable demands of the public will be materially lessened, in fact, two or possibly three sizes being sufficient to accommodate substantially the entire demand. In addition, my improved tie possesses no tendency to wrinkle, 75 and a strong tendency to return to its original shape and condition after being used, and thus constitutes an article which has substantially greater durability and usefulness than those made by previous methods. The lining not only tends to prevent wrinkling, but tends to smooth out any wrinkles or creases which the silk may have received in use upon the wearer.

80 It will be apparent that my invention is susceptible of embodiment in various different ways and in many modified forms, and I wish it distinctly understood that the form illustrated and described is for illustrative purposes only. For instance, in the illustrated tie the lining consists of two members which are joined by overlapping at the center, but, if preferred, the lining may consist of but a single member of sufficient size and shape to extend throughout such portion of 85 the tie as is required to accomplish the desired result. Again, as shown, the lining members are secured at their outer ends in a preferred way. However, other ways may be adopted and still be within the purview of 90 my invention. So, also, the lining members are overlapped and stitched to the silk at the center in the tie illustrated, but this is not essential, as the lining, whether in one or more pieces, may run free through the center of the tie and be unconnected to the silk 95 at this point. The label 12 may also be omitted, if desired.

100 In addition, while I prefer to use as a lining material a woven woolen fabric cut on the bias, yet this is not essential to accomplish some of the purposes of my invention. Other materials may be used, and, upon occasion, the lining may be cut straight. As an instance, the feature of elastic stretchability 105 may be accomplished by the use of certain woven lining fabrics which have a degree of stretchability along the lines of their warp or woof threads by reason of the special characteristics of the weave. Knitted fabrics are 110 also stretchable, and might be used to obtain certain of the features of my invention.

115 Finally, for artistic reasons, and to take advantage of various patterns, I prefer to cut the silk, of which the tie is made, on the bias, 120

but this is not absolutely necessary to accomplish some of the advantages attending upon the use of my invention. The silk may be cut straight, or in any way; or the silk itself may consist of a woven or knitted fabric; in fact, of any material to produce an attractive tie.

All of these changes are mentioned merely as illustrations, however, and not as defining the only modifications which it is possible to make; and I desire to have it clearly understood that my invention and patent protection is to be limited only within the fair purport of the appended claims.

Having thus described one form of my invention, what I claim and desire to secure by Letters Patent is:

1. The method of manufacturing neckties consisting in cutting blanks of body material to the proper shape, uniting them by stitching, securing a resilient lining to said body portion near the ends thereof, turning the tie, and securing the parts in assembled position.
2. A bow tie comprising a body portion and a resilient lining disposed therein in a flat condition throughout its entire area, secured thereto near the opposite ends thereof, and being free therefrom at all other places except at the neckband portion.
3. A tie including a sheath presenting inwardly extending marginal portions forming a pocket and a lining strip disposed within said sheath and having its end portion secured to the same adjacent the outer end of the latter, the end edge of said strip being disposed within said pocket.
4. A tie including a sheath presenting inwardly extending marginal portions forming a pocket and a lining strip disposed within said sheath and having its end portion disposed within said pocket, the inwardly extending marginal portions of the sheath and the strip end being secured to each other and the strip being solely attached to said sheath at points beyond the display portions of the latter.
